EYEGLASSES DISPLAY HOLDER

Gilbert Rios, Los Angeles, Calif., assignor to Superior Optical Company, Los Angeles, Calif.

Filed Dec. 9, 1970, Ser. No. 26,366

Term of patent 14 years

Int. Cl. D6—06

U.S. Cl. D80—9

FIG. 1.

FIG. 2.

FIG. 1 is a front perspective view of an eyeglasses display holder showing my new design; and

FIG. 2 is a rear perspective view thereof.

The broken line representation of eyeglasses in FIGS. 1 and 2 is for purposes of illustration only.

I claim:

The ornamental design for an eyeglasses display holder, as shown and described.
